UNITED STATES PATENT OFFICE.

FRANCIS E. FOULKE, OF ALBANY, NEW YORK.

ROTARY-VALVE PACKING-RING.

1,392,752.

Specification of Letters Patent.

Patented Oct. 4, 1921.

Application filed May 27, 1920. Serial No. 384,584.

To all whom it may concern:

Be it known that I, FRANCIS E. FOULKE, a citizen of the United States of America, residing at Albany, in the county of Albany 5 and State of New York, have invented certain new and useful Improvements in Rotary-Valve Packing-Rings, of which the following is a specification, reference being had therein to the accompanying drawings.

10 The invention relates to packing rings for rotary valves and has for one of its objects the provision of a construction which surrounds the port in the valve on all sides and which automatically adjusts itself to engage 15 the wall of the valve housing to take care of any wear which might occur. Other objects of the invention reside in the novel arrangements and combinations of parts as more fully hereinafter set forth.

20 In the drawings:

Figure 1 is a side elevation of a construction embodying my invention;

Fig. 2 is a cross section on the line 2—2 of Fig. 1;

25 Figs. 3 and 4 are respectively side elevations of the coöperating members of the packing ring;

1 is a hollow cylindrical rotary valve having the port 2 in its wall for controlling the 30 passage of gas to or from a cylinder 3 of an internal combustion engine, this valve being rotatably mounted inside a head or sleeve 4.

In order to seal the port 2, the metallic 35 packing ring 5 is provided. This packing ring comprises the coöperating members 6 and 7 respectively having the annuli 8 and 9 at opposite ends of the cross bars 10 and 11 and integral therewith. These cross bars extend longitudinally of the rotary valve 1 40 and engage in longitudinal grooves 12 in its wall on opposite sides of the port 2, while the annuli engage in annular grooves 13 in its wall at opposite ends of the port. The arrangement is such that the bars and annuli surround the port on all sides.

Specifically, the annuli of the coöperating member 7 of the metallic packing ring 5 rotatably engage the annuli 8 of the coöperating member 6. This coöperating member 7 50 is positioned longitudinally upon the coöperating member 6 by the flanges 14 at the outer ends of the annuli 8 which are formed by reason of the remaining portions of the annuli 8 being of reduced diameter and substantially the same as the inner diameter of 55 the annuli 9 of the coöperating member 7.

When the coöperating members are in assembled relation, the outer surfaces of the annuli 9, bars 10 and 11 and flanges 14, substantially register. The annuli 8 and 9 are 60 split transversely and the splits are preferably so arranged that the splits in the annuli of one of the members is on the side of the rotary valve opposite to the splits in the annuli of the coöperating member when the 65 parts are in assembled relation.

With the above arrangement, the coöperating members are rotatable relative to each other so that they may automatically position themselves to keep in constant contact 70 with the wall of the head or sleeve in which the rotary valve is rotatably mounted. This is an important consideration, since the metallic packing ring may properly function under all working conditions and until the 75 wear is such as to require replacement. Furthermore, the packing ring may have a minimum amount of clearance at all points and still operate efficiently, due to its flexibility and automatic positioning. Still another point is that the coöperating members 80 of the metallic packing ring form a unit and are longitudinally positioned with respect to each other without interfering with their relative rotation.

85 What I claim as my invention is:

1. The combination with a rotary valve, having a port therein, of a packing, comprising coöperating relatively rotatable members, each having a bar and annuli at opposite ends of said bar, said annuli surrounding said valve at the ends of the port and said bars being at the sides of said port.

2. The combination with a rotary valve, having a port therein of a metallic packing, comprising a member having a bar extending longitudinally of said valve and at one side of said port, and transversely split annuli at opposite ends of said bar and surrounding said valve at opposite ends of said 95 port, and a coöperating member rotatably mounted upon said first-mentioned member and comprising a bar extending longitudinally of said valve and at the side of said port opposite to said first-mentioned bar and 100 annuli at the opposite ends of said last-mentioned bar and rotatably engaging said first-mentioned annuli.

3. The combination with a hollow rotary valve having a port through its wall, and 110 annular grooves at the end of said port and longitudinal grooves at the sides of said port

and connecting into said annular grooves, of a metallic packing engageable over said valves, comprising annuli engageable in said annular grooves, and a cross bar between said annuli engageable in one of said longitudinal grooves, and a coöperating member having annuli rotatably mounted on said first-mentioned annuli and a cross bar between said last-mentioned annuli and engaging in the other of said longitudinal grooves, all of said annuli being transversely split.

4. The combination with a hollow cylindrical rotary valve having a port through its wall, and annular grooves at the ends of said port and longitudinal grooves at the sides of said port and connecting into said

annular grooves, of a packing engageable over said valve as a unit, comprising a member having annuli engaging in said annular grooves, and a cross bar engaging in one of said longitudinal grooves, said annuli having portions of reduced diameter and forming flanges at their outer ends, said packing also comprising a coöperating member having annuli rotatably mounted on said first-mentioned annuli and between said flanges and a cross bar engaging in the other of said longitudinal grooves, the outer surfaces of said last-mentioned annuli, cross bars, and flanges substantially registering.

In testimony whereof I affix my signature.

FRANCIS E. FOULKE.
